UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,271,593.

Specification of Letters Patent.

Patented July 9, 1918.

Original application filed August 19, 1914, Serial No. 857,432. Divided and this application filed January 27, 1917. Serial No. 144,879.

To all whom it may concern:

Be it known that I, RONALD A. McCANN, a citizen of the United States, residing at Swissvale, in the county of Allegheny and State of Pennsylvania, have invented certain new and useful Improvements in Railway Signaling, of which the following is a specification.

My invention relates to railway signaling and particularly to signaling for stretches of single track over which traffic moves in both directions, such for example, as stretches of single track between passing sidings.

15 The present application is a division of my co-pending application filed August 19, 1914, Serial No. 857,432, for railway signaling.

I will describe two forms of signaling systems embodying my invention, and will then point out the novel features thereof in claims.

In the accompanying drawings, Figure 1 is a diagrammatic view showing a stretch 25 of track having applied thereto one form of signaling system embodying my invention. Fig. 2 is a view similar to Fig. 1 but showing a modification of the signaling system shown therein.

30 Similar reference characters refer to similar parts in each of the views.

Referring first to Fig. 1, A—B is a stretch of single track between two passing sidings E and F, and over which stretch traffic moves in both directions. Traffic through this stretch from east to west is governed by signals S', S³ and S⁵ located at intervals in the stretch, and traffic from west to east is governed by similar signals S², S⁴ and S⁶.

35 40 Insulated joints 1 divide the stretch A—B into several successive sections A—C, C—D and D—B, and as here shown a pair of opposing signals is located near each junction of adjacent sections. Each section is further 45 divided by insulated joints 1 into two sub-sections; for example, section A—C is divided into sub-section A—G and G—C. Each such sub-section is provided with a track circuit, each track circuit comprising by 50 the rails of the sub-section, a battery b and a track relay, the latter being designated by the reference character T with the same ex-

ponent as that of the adjacent signal which governs traffic through the corresponding sub-section.

55 A signal relay is provided for the control of each signal and is designated by the reference character R, with an exponent corresponding to the exponent of the signal controlled thereby. For example, signal S³ is controlled by relay R³, signal S⁶ by relay R⁶, etc. Each signal is provided with a circuit which is controlled by the corresponding signal relay, the circuit for signal S³, for example, being from battery P³, through wires 60 2 and 3, contact 4 of relay R³, wire 5, controlling mechanism of signal S³, wire 6, contact 7 of relay R³, wires 8 and 9, common wire O to battery P³. The circuit for each of the other signals is similar to that just 65 traced for signal S³.

70 Two signal relay circuits extend through the stretch A—B, one of which normally includes in multiple the signal relays controlling the westbound signals and the other 75 of which normally includes in multiple the signal relays controlling the eastbound signals. Each of these circuits includes a series 80 of line conductors and a common return conductor O, and each circuit includes a main source of current M' or M², the source of current for each multiple circuit being located adjacent the end of the stretch at 85 which traffic governed by the corresponding signals leaves the stretch. Considering, for 90 example, the relays governing the westbound signals, which relays are R', R³ and R⁵, these relays are included in multiple in a circuit which includes the main battery M² at the west end of the stretch, this being 95 the end at which traffic governed by the corresponding signals S', S³ and S⁵ leaves the stretch. The circuit for relay R⁵ is from main battery M², through wire 10 contact 11 of track relay T², wire 12, contact 13 of 95 relay T⁵, wire 14, relay R⁵, wires 15, 16 and common return wire O to battery M². The branch for relay R³ leaves the circuit just traced at wire 14, and passes through wire 17, back point of contact 18 of a relay X⁵, 100 wire 19, back point of contact 20 of a relay X⁴, wire 21, contact 22 of relay T⁴, wire 23, contact 24 of relay T³, wire 25, relay R³, wires 26, 9, and common return wire O to

battery M^2 . The branch for relay R' leaves the branch just traced at wire 25, and is similar to the branch for relay R^3 , being controlled by track relays T^6 and T' , and by back 5 points of contacts of relays X^3 and X^6 .

The circuits for the signal relays R^2 , R^4 and R^6 for the westbound signals are similar to those just traced for the eastbound signals and are supplied with current from 10 a main battery M' located at the eastern end of the stretch.

Located adjacent each intermediate signal is an auxiliary source of current designated by the reference character P with the same 15 exponent as that of the corresponding signal. For each intermediate signal I also provide an auxiliary relay designated by the reference character X with the same exponent as that of the corresponding signal, 20 each of which relays is normally deenergized and is adapted when energized to open at that point the signal relay circuit of which the relay for the corresponding signal forms a part and to connect the corresponding 25 auxiliary source of current with the portion of such circuit extending to the rear from the point of opening. This control of the signal relay circuits will be explained in detail hereinafter, but I will first explain 30 the control of the auxiliary relays X .

Each of these auxiliary relays is provided with a pick-up and a holding circuit. For example, the pick-up circuit for relay X^3 is from battery P^3 , through wires 2 and 27, contact L^6 (controlled by signal S^6), wire 28, contact L^3 (controlled by signal S^3), wires 35 29 and 30, contact 31 of relay R^3 , wires 32 and 33, relay X^3 , wire 34, back point of contact 35 of relay X^6 , wires 36, 9, and O to battery P^3 . Hence, in order to energize relay X^3 , signal S^6 must be at "stop," and signal S^3 at "proceed," relay R^3 must be energized, and relay R^6 must be deenergized. 40 This pick-up circuit is provided with a 45 branch around contact 31 of relay R^3 , which branch comprises wire 37, back point of contact 38 of relay T^3 and wire 39. The holding circuit for relay X^3 is from battery P^3 , through wires 2 and 40, back point of contact 50 41 of relay R^3 , wire 42, contact 43 of relay X^3 , wires 44 and 33, relay X^3 , wire 34, back point of contact 35 of relay X^6 , and wires 36, 9 and O to battery P^3 . It will be seen, therefore, that this holding circuit is 55 closed only when X^3 has previously been energized and relay R^3 is deenergized, it also being necessary that relay X^6 be deenergized. The control circuits for each of the other auxiliary relays are similar to those 60 just traced for relay X^3 .

It will be seen from the foregoing that the pick-up circuits for the auxiliary relays are controlled mainly by the signal relays R and by circuit controllers operated by the 65 signals themselves, each of which circuit con-

trollers is designated by the reference character L with the same exponent as that of the corresponding signal.

The operation of the system shown in Fig. 1 during the passage of a westbound car or train through the stretch A—B is as follows: As the train enters sub-section B—K, it opens track relay T' , thereby opening at contact 45 the circuit for signal relay R' , so that signal S' moves to the "stop" position. 75 The multiple circuit including signal relays R^6 , R^4 and R^2 is opened at contact 46 of relay T' , so that all of these relays become deenergized and thus allow signals S^6 , S^4 and S^2 to move to the "stop" position. Consequently, as soon as a car or train enters 80 sub-section B—K moving toward the west, the first westbound signal S' and all of the signals governing traffic in the opposite direction, that is, from west to east, will move 85 to the "stop" position. The movement of signal S^6 to the "stop" position closes the pick-up circuit for auxiliary relay X^3 , and the movement of signal S^4 closes the pick-up circuit for auxiliary relay X^5 , so that both 90 of these auxiliary relays become energized as soon as the westbound car or train enters that stretch. As the train proceeds and enters sub-section D—K, it opens track relay T^6 , but this causes no change in the signal 95 circuits, because the latter track relay exerts the same control over the circuits now involved as does track relay T' . As the train proceeds into sub-section H—D, it opens track relay T^3 , which in turn opens 100 the circuit for relay R^3 , and this latter relay, of course, causes signal S^3 to move to the "stop" position. The opening of contact 31 of relay R^3 opens the pick-up circuit for relay X^3 for a moment before the holding 105 circuit for this relay becomes closed at contact 41, but during this interval relay X^3 continues to be energized because of the branch in its pick-up circuit including contact 38 of track relay T^3 , which branch 110 serves as a shunt around contact 31 of relay R^3 . Auxiliary relay X^3 being closed, the multiple circuit for the westbound signal relays is opened at contact 48, but auxiliary battery P^3 is now connected with relay R' 115 through the front point of this contact 48, so that as soon as the entire car or train leaves sub-section D—K, thus allowing track relay T^6 to close, relay R' becomes energized so that signal S' returns to the "proceed" 120 position. The circuit for relay R' is now from battery P^3 through wires 2 and 47, front point of contact 48, wire 49, contact 50, wire 51, thence through the contacts of track relays T^6 and T' , relay R' , back to battery 125 P^3 . The closing of track relay T^6 as the train leaves sub-section D—K, closes the circuit for relay R^6 so that signal S^6 returns to the "proceed" position. The movement of signal S' to the "proceed" position per- 130

mits a following westbound car or train to enter the stretch. As the first car or train passes out of sub-section H—D and into sub-section C—H, it opens track relay T⁴ and then allows track relay T³ to close, but inasmuch as these relays control the same circuits so far as now involved, the change will have no effect on the signals. Auxiliary relay X³ continues to be energized owing to the fact that relay R³ is deenergized, hence, signal S' continues to indicate "proceed". As the car or train passes from sub-section C—H into sub-section G—C, it opens track relay T⁵ and signal relay R⁵, and allows track relay T⁴ to close. The opening of relay R⁵ causes signal S⁵ to move to the "stop" position and also closes the holding circuit for auxiliary relay X⁵. Relay X⁵ now opens the circuit for relay R⁵ at the back point of contact 18 and connects this circuit with battery P⁵ through the front point of contact 18, so that relay R⁵ now becomes energized from battery P⁵ and so allows signal S⁵ to move to the "proceed" position, thus permitting a following westbound car or train to enter section C—D. The closure of relay R³ opens the holding circuit for relay X³ so that relay R' is then disconnected from battery P³, but this relay continues to be energized because it is now connected with battery P⁵. Of course, if a following westbound train occupies section D—B it holds relay R' open. The opening of relay X³ closes the circuit for relay R⁴ which latter then becomes energized so that signal S⁴ returns to the "proceed" position. As the first car or train leaves the section A—C, relay R⁵ becomes energized from battery M² and so deenergizes relay X⁵. Relays R⁵, R³ and R' are thus again energized from main battery M² so that the multiple circuit for the relays controlling the eastbound signals is then restored to its normal condition. Signal S², of course, returns to the "proceed" position as the car or train leaves sub-section A—G. All parts of the system are now restored to the conditions in which they are shown in the drawing.

The operation of the system during the passage of an eastbound car or train through the stretch is similar to that just explained for the operation during the passage of a westbound car or train.

Referring now to Fig. 2, in the form here shown the arrangement of signals and relays is the same as in Fig. 1. The control of each signal by the corresponding relay is also the same as in Fig. 1, but the control of the relays R is different from that shown in Fig. 1 as is also the control of the auxiliary relays X.

In Fig. 2 each signal relay is controlled by a contact on the signal relay for the signal next in advance governing traffic in the same direction. For example, relay R' is

controlled by contact 54 of relay R³, the circuit being from battery P³ through wires 52 and 53, contact 54 of relay R³, wire 55, back point of contact 56 of relay X⁶, wire 57, contact 58 of relay T⁶, wire 59, contact 70 60 of relay T⁶, wire 61, relay R', wire 62 and O to battery P³. Similarly, relay R³ is controlled by track relays T³ and T⁴ and by contact 82 of relay R⁵, while relay R⁵ is controlled by track relays T² and T⁵. In like manner relay R² is controlled by relay R⁴ and relay R⁴ is controlled by relay R⁶.

The circuit for relay R' is provided with a branch around contact 54 of relay R³, which branch is controlled by relay X³ and 80 is from wire 52, through wire 63, contact 64, wire 65 to wire 55. Similarly, the circuit for each relay R is provided with a branch around the signal relay contact which normally controls such circuit. The circuits for 85 relays R⁵ and R⁶ are not provided with such branches, because, in the form here shown, these relays are not controlled by other signal relays.

Each auxiliary relay X is provided with 90 a pick-up circuit governed by signal operated circuit controllers L, and with a holding circuit governed by signal operated circuit controllers N. For example, the pick-up circuit for relay X³ is from battery 95 P³, through wire 66, back point of contact 67 of relay X⁶, wire 68, contact L⁶, wire 69, contact L³, wires 70 and 71, relay X³, wires 72, 73 and O to battery P³. It will be seen that this circuit is closed only when signal 100 S⁶ indicates "stop", signal S³ indicates "proceed", and relay X⁶ is deenergized. The holding circuit for relay X³ is from battery P³, through wires 52 and 74, contact N³, wire 75, contact 76 of relay X³, wires 77 105 and 71, relay X³, wires 72, 73 and O to battery P³. This circuit, it will be seen, is closed only when signal S³ indicates "stop" and relay X³ has previously been energized. This circuit is provided with a branch around 110 contact N³, which branch extends from wire 52, through wire 78, back point of contact 79 of relay T³ and wire 80 to wire 75. Each of the other auxiliary relays X is provided with a pick-up and a holding circuit, which 115 circuits are similar to those just traced for relay X³.

The operation of the system shown in Fig. 2 during the passage of a westbound car or train through the stretch is as follows: 120 As the car or train enters sub-section K—B, it opens relay T', which relay opens at contact 60 the circuit for relay R', whereby signal S' is caused to move to the "stop" position. Relay T' also opens at contact 81 the 125 circuit for relay R⁶, whereby signal S⁶ moves to the "stop" position. Relay R⁶ opens relay R⁴ and relay R⁴ opens relay R², whereby signals S⁴ and S² likewise move to the "stop" position. As the train proceeds 130

into section D—K, no change is effected, because track relay T^6 controls the same circuits now involved as relay T' . The movement of signal S^6 to the "stop" position 5 closed the pick-up circuit for relay X^3 and the similar movement of signal S^4 closed the circuit for relay X^5 . As the car or train enters sub-section H—D, it opens relay T^3 , which in turn opens relays R^3 , whereby signal S^3 moves to the "stop" position. This 10 movement of signal S^3 closes contact N^3 and thus closes the holding circuit for signal X^3 , but during the interval between the opening of contact L^3 and the closure of contact N^3 15 a temporary holding circuit is closed for relay X^3 through contact 79 of relay T^3 , thus avoiding any possibility of an accidental opening of relay X^3 . When the entire car or train passes out of sub-section D—K 20 the closure of track relay T^6 allows signal S^6 to return to the "proceed" position, and although the circuit for relay R' is now open at contact 54 of relay R^3 , this circuit is closed at contact 64 of relay X^3 so that 25 signal S' returns to the "proceed" position. Similarly, as the car or train passes the point C, it allows signal S^4 to return to the "proceed" position, and it also allows signal S^3 to return to this position, even though the 30 circuit for relay R^3 is open at contact 82 of relay R^5 . As the entire car or train leaves the stretch, signals S^2 and S^5 return to the "proceed" position, so that all parts of the system resume the positions in which they 35 are shown in the drawings.

The operation of the apparatus during the passage of an eastbound car or train through the stretch is similar to the operation just described during the passage of a 40 westbound car or train.

Although I have herein shown and described only two forms of railway signaling embodying my invention, it is understood that various changes and modifications may 45 be made therein within the scope of the appended claims without departing from the spirit and scope of my invention.

Having thus described my invention, what I claim is:

50 1. In combination, a stretch of railway track divided into track-circuited sections, signals located at intervals for governing traffic through the stretch, means for controlling each signal by each track circuit in advance of the signal, an auxiliary relay corresponding to each signal for rendering the track circuits in advance thereof ineffective to control the signal next in the rear, a pick-up circuit for each auxiliary relay controlled by one or more track circuits in advance of the corresponding signal and by a contact operated by an adjacent signal governing traffic in the opposite direction which contact is closed only when the signal 55 indicates "stop", and a holding circuit for

each auxiliary relay controlled by one or more track circuits in advance of the corresponding signal.

2. In combination, a stretch of railway track, signals located at intervals for governing traffic through the stretch, a signal relay for each signal, means for controlling each signal relay by the signal relay for the signal next in advance governing traffic in the same direction, track circuits for the stretch including track relays for controlling said signal relays, an auxiliary relay corresponding to each signal for rendering the signal relay for such signal ineffective to control the signal relay for the signal in the rear, a pick-up circuit for each auxiliary relay controlled by one or more track circuits in advance of the corresponding signal and by a contact operated by an adjacent signal governing traffic in the opposite direction which contact is closed only when the signal indicates "stop", and a holding circuit for each auxiliary relay controlled by one or more track circuits in advance of the corresponding signal. 90

3. In combination, a stretch of railway track divided into a plurality of successive sections, a pair of opposing signals located adjacent each junction of two sections, a signal relay for each signal, a circuit for each signal relay which circuit is controlled by the signal relay for the signal next in advance governing traffic in the same direction, track circuits for the stretch including track relays for the control of the signal relays, auxiliary relays one for each signal for rendering the corresponding signal relay ineffective to control the relay for the signal next in the rear, contacts operated by the signals, a pick-up circuit for each auxiliary relay including a contact operated by the corresponding signal and closed when the signal indicates clear, and a contact operated by the adjacent signal governing traffic in the other direction and closed when the signal indicates danger, and a holding circuit for each auxiliary relay including a back contact of the track relay for the track circuit immediately in advance of the corresponding signal and a front contact of the auxiliary relay. 105

4. In combination, a stretch of railway track divided into a plurality of successive sections, a pair of opposing signals located adjacent each junction of two sections, a signal relay for each signal, a circuit for each signal relay which circuit is controlled by the signal relay for the signal next in advance governing traffic in the same direction, track circuits for the stretch including track relays for the control of the signal relays, auxiliary relays one for each signal for rendering the corresponding signal relay ineffective to control the signal relay for the signal next in 110 120 125 130

- the rear, contacts operated by the signals, a pick-up circuit for each auxiliary relay including a contact operated by the corresponding signal and closed when the signal indicates clear, and a contact operated by the adjacent signal governing traffic in the other direction and closed when the signal indicates danger, a holding circuit for each auxiliary relay including a contact operated by the corresponding signal and closed when the signal indicates danger, and a
- 5 branch for each holding circuit around said signal operated contact and including a back contact of the track relay for the track circuit immediately in advance of the corresponding signal.
- 10 In testimony whereof I affix my signature in presence of two witnesses.

RONALD A. McCANN.
